(57) **CLAIM**

The ornamental design for an arm positioning device, as shown and described.

DESCRIPTION

FIG. 1 is a perspective view of an arm positioning device of our new design.

FIG. 2 is a close-up perspective view thereof.

FIG. 3 is a front end view thereof.

FIG. 4 is a rear end view thereof.

FIG. 5 is a right side view thereof.

FIG. 6 is a left side view thereof.

FIG. 7 is a top view thereof.

FIG. 8 is a bottom view thereof.

FIG. 9 is a perspective view thereof in an open configuration for installation onto arms of a patient; and,

FIG. 10 is a perspective view thereof showing a patient wearing the arm positioning device.

The broken lines in the drawings depict environmental subject matter and form no part of the claimed design.

1 Claim, 6 Drawing Sheets
